UNITED STATES PATENT OFFICE.

GEORGE F. DOWNS AND HERBERT F. MILLER, JR., OF BUFFALO, NEW YORK; SAID MILLER ASSIGNOR TO SAID DOWNS.

PORT CONSTRUCTION FOR METALLURGICAL FURNACES.

1,343,314.

Specification of Letters Patent. Patented June 15, 1920.

Application filed March 30, 1918. Serial No. 225,647.

To all whom it may concern:

Be it known that we, GEORGE F. DOWNS and HERBERT F. MILLER, Jr., citizens of the United States, and residents of Buffalo, in 5 the county of Erie and State of New York, have invented certain new and useful Improvements in Port Construction for Metallurgical Furnaces; and we do hereby declare that the following is a full, clear, and exact 10 description thereof, reference being had to the accompanying drawings, and to the letters of reference marked thereon, which form a part of this specification.

This invention relates to a novel and useful improvement in the port construction of 15 metallurgical furnaces and consists of the matters hereinafter described and more particularly pointed out in the appended claims.

In metallurgical furnaces as usually built 20 and particularly in open hearth furnaces, the fuel is passed from the gas port into the hearth of the furnace in such manner that it obtains oxygen for combustion, from an overhead layer of air, while the bottom of 25 the body of fuel, as it flows into the hearth, is in contact with the bottom of the port and with the charge in the hearth.

As a result of this arrangement, and the 30 location of the air containing the oxygen for combustion above the body of fuel, the fuel does not develop the proper flame temperature next to the bath, where it is needed, until such time elapses as is required for the air to diffuse through to the bottom layer of 35 the body of gaseous fuel.

This condition is clearly indicated by the appearance of that portion of the charge which has been directly under the gas or fuel as it issued from the port, which, when 40 the gas is shut off, is observed to be much darker in appearance than the rest of the charge. The interpretation of this appearance of the charge is that while the rest of the charge may be melting or gaining heat, 45 the portion that remains dark, is a freezing surface. That is, when the charge or bath has reached a higher temperature than that of the fuel as it issues from the port, that portion of the bath or charge that is in contact with the fuel as it comes into the hearth, 50 gives up heat to the body of gas until a point is reached where the fuel is ignited by the overhead layer of air, and at this point the melting and heating of the charge 55 starts.

Another disadvantage of the port construction of the present practice, is that there is no satisfactory means for correcting the direction of the flame once the furnace is put in operation, unless the furnace 60 is shut down and expensive repairs are made. The lack of means for changing the direction of the flame while the furnace is in operation causes exceedingly costly and frequent repairs. 65

One object of our invention is to provide a novel port construction which by its use will eliminate the inert or freezing area in that portion of the charge that is directly under the gas, by converting the said area 70 into a melting or heating surface. Another object of the invention is to provide facilities to control the direction of the flame while the furnace is in operation. These and other advantages of our invention will 75 appear as we proceed with our specification.

In the drawings:

Figure 1 is a view representing in longitudinal section, one end of an open hearth 80 furnace provided with our improvements.

Fig. 2 is a view representing a horizontal section through Fig. 1 in a plane indicated by the line 2—2 thereof.

Fig. 3 is a view representing a vertical 85 section through Fig. 1 in a plane indicated by the line 3—3 thereof.

Fig. 4 is a view representing a vertical section through Fig. 1 in a plane indicated by the line 4—4 thereof. 90

Fig. 5 is a view representing a partial section through the improved port construction in a plane indicated by the line 5—5 of Fig. 1.

Fig. 6 is a view representing a partial 95 section through Fig. 1 in a plane indicated by the line 6—6 thereof.

Referring now to that embodiment of our invention illustrated in the drawings:—10 indicates as a whole, an open hearth furnace 100 provided with our improved port construction, and 11, the furnace chamber. (See Figs. 1 and 2.) 12 indicates the gas uptake; 13, the air uptake; 14 indicates the gas port and 15, the air port. 105

16 indicates a gas flue, which provides the connection between the gas uptake 12 and the furnace chamber 11. Said flue is, as shown, of the kind described in an application heretofore filed by George F. Downs on 110

March 5, 1918, Serial Number 220,454. It is made of metal and consists of two concentrically arranged, radially spaced, tubular members 17, 18 which are connected together at their ends to provide a cooling water jacket space 16^a surrounding the port or flue space defined by the inner tubular member 18.

10 The flue 16 is positioned in the port of the furnace over the air uptake 13 and has its outer end extended into the gas uptake 12 through an opening in the upright wall 12^a that separates the gas uptake from the air uptake.

15 This opening in the wall 12^a is of a diameter somewhat greater than that of the flue 16, which extends through it to permit of an adjustment of the longitudinal axis of said flue with reference to the furnace chamber, after which the annular space between that part of said wall 12^a defining said opening and said flue is filled with some comparatively soft material 12^b, such as a cementitious mixture of brick dust, which may 25 be easily removed when a new adjustment of said flue is desired. When this new adjustment has been made, said space is again filled up as before mentioned.

The flue 16 is supported in position by 30 two pipes 19, 20, located at the ends of the flue and connected to the outer tubular member 17 in such a manner as to communicate with the interior of the jacket space 16^a. Said pipes serve for the introduction into, 35 and discharge from, the jacket space of a cooling medium such as water,—the pipe 19 being the discharge pipe and the pipe 20 being the inlet pipe. Flexible hose 19^a, 20^a, are connected to the upper ends of said 40 pipes,—the hose 20^a leading from a source of water supply, and the pipe 19^a leading to a place for suitable disposal of the water after it has passed through the jacket space 16^a.

45 Each pipe (19, 20) is suspended by means of a screw device 21 mounted on a transverse beam 22 that is suitably supported above the top of the furnace. Said screw device consists of a threaded block 23 in 50 which is engaged a tubular thimble 24 through which the associated pipe 19, 20 extends, a collar 25 fixed to the pipe 20 engaging on the top end of said thimble and the thimble itself being provided with radial 55 arms 26 for hand rotating it to raise or lower the pipe.

The pipe 19 is located outside the end wall of the furnace as shown. The pipe 20 extends through an opening 28 in the top wall 60 11^a of the furnace, being provided with a covering 27 of refractory material such as that composed of sectional sleeve brick shown.

When it is desired to regulate the height 65 and inclination of the longitudinal, central

axis of the gas flue 16 in a vertical plane, the soft filling 12^b is removed from the hole in the wall 12^a, after which the screw devices 21, 21, are actuated to raise or lower said flue, the bottoms of the collars 25 being 70 provided with spherical surfaces 25^a to facilitate the adjustment. The flue may also be adjusted at its inner end in a horizontal direction, by means of a horizontal rod 29 which is connected at one end by a collar 29^a 75 to the pipe 20 and at its other end has a threaded part 30 engaged in a rotatable block 31 provided with a hand wheel 32. The block 31 is fixed in a horizontal direction, although capable of rotative movement, 80 so that the rotation of the block will cause the rod 29 to move longitudinally in one direction or the other so as to swing the pipe 20 and with it, the inner end of the flue 16, in a horizontal direction.

85 After the desired adjustment has been made, a new soft filling 12^b, is used to again close up the space about the flue 16. While this is the preferred method of providing for the adjustment of the flue, said flue by 90 reason of its being suspended independently of any wall, permits the brick of that wall 12^a, through which the flue extends, to be partly removed, so that the flue is free to be adjusted as before described, after which 95 the bricks may be easily replaced so as to surround said flue.

The inner end of the flue 16 is, as clearly illustrated in the drawings (see Figs. 1, 3 and 4), free and clear of the walls defining 100 the air port 15, so that the air coming from the air uptake 13 will completely surround the body of fuel as it passes from the gas flue to the hearth in the furnace chamber 11. Thus, the air from the uptake will supply 105 oxygen to the fuel as it leaves the flue 16 in such manner as to ignite from the bottom of the fuel body that is in direct contact with the charge, as well as igniting from the top in the manner heretofore.

110 The refractory sleeve 27 insures the delivery of the water in a cool condition to the jacket space around the flue and this water is introduced at a lower level than the level of discharge, as is manifest from an examination of Fig. 1.

The flue, as shown, is provided with a cleaning device which consists of a pipe 33 extending longitudinally between the walls of the jacket space 16^a and in a direction parallel to the longitudinal, central axis of the flue. This pipe is provided at its inner end with a curved, discharge or nozzle pipe 34, perforated for the discharge of air under pressure. The outer end of the pipe 33 extends through a pipe 36 of larger diameter which is provided at its outer end with a stuffing box 37, this construction being required because the cooling water discharge is at a higher level than the end of the pipe 130

36. The cleaning device is of the type described in the application hereinbefore mentioned. It is connected at its outer end by a flexible hose 33^a to any source of air or other 5 suitable fluid under pressure, and is provided with a handle 33^b for operating it and causing it to reciprocate back and forth in the jacket space 16^a of the gas flue, and with a hand valve 33^c for controlling the air supply. 10 From the foregoing description, it will be apparent that our novel port construction provides means for introducing air from the air uptake at an elevation below the body of the fuel or gas introduced into the furnace 15 chamber and directed toward the hearth of a furnace of the kind described. This is a distinctly novel departure from the practice heretofore of introducing the air through a passageway or port above or at a higher 20 elevation than the body of the fuel entering through the gas port. In our construction, the fuel or gas as it escapes from the orifice of the gas flue, is entirely surrounded by pre-heated air before it reaches the hearth, 25 with the result that the freezing area of the charge that has heretofore maintained in furnaces of the kind, is entirely eliminated. In addition, in the improved construction, means is provided for adjusting from the 30 outside of the furnace, the position of the gas flue in a vertical and horizontal direction during the operation of the furnace, so as to change or correct the direction of the flame upon the charge on the hearth. 35 While in describing our invention, we have referred to certain details of construction and arrangement of parts, it is to be understood that our invention is in no way to be limited thereto, except as may be pointed 40 out in the appended claims.
- We claim as our invention:—
1. In a furnace of the kind described, in combination with the furnace walls defining gas and air uptakes and an air port connecting the air uptake with the interior of the furnace, means providing a flue extending into said air port to connect the gas uptake with the interior of the furnace, and adjustable means operable from without that wall 45 of the furnace providing the top wall of the air port for supporting said flue so that said air port entirely surrounds the orifice of said flue.
  2. In a furnace of the kind described, in combination with the furnace walls defining gas and air uptakes and an air port connecting the air uptake with the interior of the furnace, means providing a water-cooled tubular metal flue extending into said air 55 port to connect the gas uptake with the interior of the furnace, and adjustable means operable from without that part of the furnace providing the top wall of the air port for so supporting said flue that it is entirely 60 surrounded by said air port.
  3. A flue to connect the gas or fuel uptake of a furnace of the kind described with the furnace chamber, said flue completely inclosing, surrounding and directing the gas or fuel on its way from the gas or fuel uptake to the point where it joins the air entering the furnace chamber, and means for adjusting said flue from the outside of the furnace, for controlling the direction of the flow of the fuel. 70
  4. A flue to connect the gas or fuel uptake of a furnace of the kind described with the furnace chamber, said flue completely inclosing, surrounding and directing the gas or fuel on its way from the gas or fuel uptake to the point where it joins the air entering the furnace chamber, and means for supporting said flue, said means including devices for adjusting the flue from the outside of the furnace to control the direction of the flow of fuel therethrough. 80
  5. In a furnace of the kind described, in combination with the gas and air uptakes, means providing a water cooled, metal flue to connect the gas uptake with the interior 90 of the furnace, said flue completely inclosing, surrounding and directing the gas or fuel, means providing an air port completely surrounding the orifice of said flue, and devices for supporting said flue, said devices 95 including adjusting means operable from the outside of the furnace for determining the position of the longitudinal, central axis of said flue.
  6. In a furnace of the kind described, in combination with the gas and air uptakes, means providing a water cooled, metal flue to connect the gas uptake with the interior of the furnace, said flue completely inclosing, surrounding and directing the gas or 100 fuel, means providing an air port completely surrounding the orifice of said flue, devices for supporting said flue comprising inlet and discharge pipes, and adjusting devices supported outside of the furnace adapted to 105 determine the position of the longitudinal, central axis of said flue.
  7. In a furnace of the kind described, in combination with the gas and air uptakes, a flue to connect the gas uptake with the interior of the furnace, means providing a passageway for the air into the interior of the furnace, means extending through the top wall of the furnace for supporting said flue in said air passageway so that said flue is 115 completely surrounded by the same, and means operable from without the furnace for adjusting said gas flue vertically or horizontally in said air passageway.
  8. In a furnace of the kind described, in combination with the gas and air uptakes, a water cooled, tubular, metal flue to connect the gas uptake with the interior of the furnace, means providing a passageway for the air into the interior of said furnace, means 125

for supplying and discharging a cooling water to and from said water cooled, tubular, metal flue, and means for adjustably supporting said flue in said air passageway so as 5 to completely surround the same, without disturbing the supply and discharge of said cooling water to and from said water cooled flue.

9. In a furnace of the kind described, in 10 combination with the gas and air uptakes, a water cooled, tubular, flue to connect the gas uptake with the interior of the furnace, means providing a passageway for the air into the interior of the furnace, and water 15 cooled means for adjustably supporting said water cooled gas flue in said air passageway so that said flue is completely surrounded by the same, said adjustable supporting means being capable of being operated from 20 without the furnace.

10. In a furnace of the kind described, in combination with the gas and air uptakes, a flue to connect the gas uptake with the interior of the furnace, means providing an 25 air port surrounding the orifice of said flue, said flue comprising concentrically arranged, inner and outer metal tubes joined at their ends to form a jacket space for a cooling medium, pipes connected to said gas flue at 30 its ends, said pipes forming the inlet and discharge for the cooling medium to and from said jacket space, and means for ad-

justably supporting said pipes without the furnace, adapted for determining the position of the longitudinal central axis of said 35 flue.

11. In a furnace of the kind described, in combination with the gas and air uptakes, a flue to connect the gas uptake with the interior of the furnace, means providing an 40 air port surrounding the orifice of said flue, said gas flue comprising concentrically arranged, inner and outer metal tubes joined at their ends to form a jacket space for a cooling medium, pipes connected to said gas 45 flue at its ends and extending vertically above the furnace, said pipes forming the inlet and discharge of the cooling medium to and from said jacket space, collars on said pipes without the furnace, hand screw devices supporting said collars and adapted to raise or lower the same, and means without the furnace and connected to one of said pipes for imparting a horizontal, adjusting movement to the orifice end of the flue. 50

In testimony that we claim the foregoing as our invention, we affix our signatures in the presence of two witnesses, this 26 day of March, A. D. 1918.
